METHOD OF AND MEANS FOR FREQUENCY STABILIZING SIGNAL GENERATORS

Lowell E. Norton, Princeton Junction, N. J., assignor to Radio Corporation of America, a corporation of Delaware

Application February 26, 1945, Serial No. 579,766

17 Claims. (Cl. 250—36)

1

This invention relates generally to signal generating systems, and more particularly to improved methods of and means for stabilizing the frequency of signal generating systems by means of control resonator networks.

Close frequency control of magnetrons or other ultra-high frequency generators has become of increasing importance due to the widespread use of such devices as sources of ultra-high frequency energy. Frequency stabilization is particularly necessary when the magnetron or other high frequency source must operate unattended for comparatively long intervals during which ambient temperatures, terminal impedances, operating potentials and currents and magnetic field characteristics may fluctuate or vary between wide limits.

The methods of and means for frequency stabilizing such devices, to be described in detail hereinafter, may be employed at any frequency. They are particularly convenient when the frequency is sufficiently high so that the use of waveguide or transmission line sections having distributed reactance characteristics are feasible. At lower frequencies, artificial lines comprising lumped circuit components may be substituted for lines having distributed constants. At any frequency, equivalent circuits comprising combinations of suitable mutual reactances, lumped or distributed reactances and resistances, may be employed.

It is well known that a generator which includes two resonant circuits having relatively widely differing "Q" values will be controlled by the resonant circuit having the higher "Q" value, and effectively controlled if the higher "Q" circuit has the lower resonant resistance. It also is well known that other parameters being equal, higher "Q" resonant circuits, provide improved frequency stability in such generators.

Heretofore, high frequency oscillators and magnetrons have been frequency-stabilized (a) by parallel-connecting a high "Q" control resonator with the load and generator or, (b) by parallel-connecting a high "Q" control resonator which is transformed to a lower resultant impedance in an intermediate stage, said transformed resonant circuit being shunt-connected with the load and oscillator. The relative advantages of these systems are discussed in greater detail herein-after. However, they both have inherent limitations which prevent the high degree of frequency stability necessary for many high frequency signal transmission systems.

The instant invention provides improved fre-

2

quency stability over that attainable with prior systems, and although somewhat unorthodox in theory and application, it is readily adaptable to the frequency stabilization of signal generators at any frequency. The frequency stabilizing network comprises a high "Q" impedance of a complex nature which is transformed to a new impedance with a higher "Q" and lower absolute value, and which is then parallel-resonated with another reactance of opposite sign. The "synthetic" control resonator thus provided is parallel-connected to the generator and load to stabilize the frequency of the generator.

Circuit elements having rapid rates of change of phase angle with frequency and critical optimum line lengths may be determined, as described in detail hereinafter, to provide practical circuit configurations. It is emphasized that the instant system differs from previous practice

15 20 25 30 35 40 45 50

wherein the reactive elements of a high "Q" resonator are first combined, and then transformed to new values, the transformed resonator impedance being shunt-connected with the generator and load.

Use of the instant invention has been found to provide frequency stability of one part in twenty thousand at 10,000 megacycles per second for changes in ambient temperatures of 50° C. It also provides frequency stabilization to one part of twenty thousand for 3:1 changes in magnetron current in a magnetron generator. Furthermore, the system is effective in reducing frequency shifts due to variations in load impedance. For any terminal impedance of random phase and magnitude which will provide a standing wave ratio of not more than 1.5 in a waveguide system connecting the load and the stabilizer system, it is possible to limit the frequency shift to one part in fifteen thousand over the entire range of terminal impedances represented by these conditions. The improved operation is due to the fact that the theoretical limit of the resultant effective "Q" of the control impedance may be shown to be one half of the squared value

$$\left(\frac{Q^2}{2}\right)$$

55 of the "Q" of the control impedance. The limiting factor is the loss in the impedance transformation.

Among the objects of the invention are to provide improved methods of and means for stabilizing the output frequency of signal generators. Another object is to provide improved methods of and means for synthesizing control resonant cir-

cuits for stabilizing frequency generators. An additional object of the invention is to provide improved methods of and means for synthesizing a high "Q" resonant circuit. A further object is to provide improved methods of and means for effectively raising the "Q" of a resonant circuit. Another object is to provide improved methods of and means for frequency-stabilizing signal generators for variations in ambient temperature, operating voltages and currents, and variations in terminal impedance. A still further object of the invention is to provide improved methods of and means for providing a high "Q" resonant circuit wherein a high "Q" impedance is transformed to a lower impedance value having a higher "Q," and then said transformed impedance is parallel-resonated with a reactance of opposite sign.

The prior art and the instant invention, both as to theory and practical circuit configurations, will be described in greater detail by reference to the accompanying drawings of which Figures 1 to 13 are schematic circuit diagrams illustrating the mathematical discussion of the features of the invention, Figure 14 is a graph illustrating said mathematical treatment of the invention, Figure 15 is a fragmentary perspective view of the coupling between the generator and the stabilizing network, Figure 16 is a side elevational view of a first embodiment of the invention, Figure 17 is a cross-sectional end elevational view of said first embodiment of the invention taken along the section line XVII, and Figure 18 is a perspective view of a second and preferred embodiment of the invention. Similar reference characters are applied to similar elements throughout the drawing.

Any oscillator or generator used as a source of energy has certain characteristics which for convenience may be expressed in terms of impedance concepts. The resulting equivalent circuits may contain many elements which may or may not be linear with certain parameters such as frequency. However, under any one set of operating conditions, this complicated equivalent circuit may always be replaced by a "characteristicless" potential, e , which is independent of frequency or external impedances, and a single impedance, Z_{int} , as shown in Figure 1. If the operating parameters are changed even slightly it is possible for the new, simple equivalent circuit to contain a radically different potential and impedance.

The generator 1, may be considered as having load terminals t_3 and t_4 . It would be advantageous to have terminals t_1 and t_2 available, but terminals t_3 and t_4 are the only ones which are accessible. However, if Z_{int} is of the form

$$Z_{int} = r_{int} + ix_{int} \quad (1)$$

it will always be possible, by proper choice of an external circuit, to tune out the reactive term with an external series reactance x_{ext} which is

$$x_{ext} = -x_{int} \quad (2)$$

so that the oscillator may then be represented by the potential, e , in series with the resistance, r_{int} .

In Figure 2 the oscillator is shown as connected to any external terminal impedance composed of m branches each of which contains m_n branches. If all of the elements in the external circuit of Figure 2 are pure reactances, with no real terms and if $r_{int} \rightarrow 0$, then the actual external circuit configuration is unimportant since the rate of phase change, with frequency, of the external circuit at

terminals t_3-t_4 no longer depends upon the actual circuit configuration.

Actually a circuit with this limitation is of no value since by specifying that the elements are all reactive, it is assumed that the system will not be allowed to radiate or to supply power to a load. To be useful, at least one of the impedances of the external circuit must be complex and therefore contain a real term. By introducing only one real term in the external circuit of Figure 2 the actual circuit configuration becomes important since the rate of phase change, with frequency, at terminals t_3-t_4 will depend upon the particular configuration.

If Z_{int} is controllable, then it must be so chosen that a large rate of phase change with frequency at t_3-t_4 will also produce a large rate of phase change at t_1-t_2 . If there is no control of x_{int} , then the external circuit must produce a large rate of phase change with frequency at t_1-t_2 and not necessarily at t_3-t_4 .

One other practical restriction must be imposed on the external circuits. At very high frequencies it is difficult to measure impedances and other quantities related to potentials and currents in composite circuits. Therefore, the final circuit must not be so complex as to preclude the possibility of accurate adjustments of the circuit elements. Also, if possible, critical and radical changes in circuit operation which will be easily detectable in monitoring equipment used during adjustment should occur near optimum adjustment of critical circuit values, so that proper initial adjustment may be made.

Obviously, an infinite number of circuit configurations is possible. To insure a correct approach to the problem without becoming quite hopelessly involved in too many possible circuit forms, it is desirable to make certain reasonable approximations which transform the problem to a much simpler one. The validity of these initial approximations may be examined when a tentative stabilizing network has been found.

COMPARISON OF FREQUENCY STABILIZATION SYSTEMS

METHOD I—PARALLEL RESONATORS

Any oscillator 1, as shown in Figure 1, will have a certain inherent frequency stability so that Z_{int} may be defined in terms of $|Z_{int}|$ and an equivalent Q . The elements which determine this Q may be actual physical elements or equivalent elements which may be due, for example, to electron beam loading of resonators.

Let the Q of the oscillator 1 be Q_3 , and the parallel impedance associated with the Q_3 be

$$Z_{03} = R_{03} + ix_{03} \quad (3)$$

To observe the impedance-frequency characteristics of this parallel resonant circuit, it is convenient to use the simple arrangement of Figure 3. Let the frequency change from f to $f(1+\delta)$ where $\delta \ll 1$. The reactances in Figure 3b have values x_3 and x_3' at $\delta=0$.

Then

$$Z_{03} = \frac{[R_3 + ix_3(1+\delta)] \left[-\frac{ix_3'}{1+\delta} \right]}{R_3 + ix_3 + ix_3\delta - \frac{ix_3'}{1+\delta}} \quad (4)$$

This reduces to

$$Z_{03} = x_3 \frac{\frac{R_3 x_3'}{(1+\delta)^2} + i \left[\frac{x_3 x_3'}{(1+\delta)} - x_3^2 (1+\delta) - \frac{R_3^2}{1+\delta} \right]}{R_3^2 + \left[\frac{x_3 (1+\delta)^2 - x_3'}{1+\delta} \right]^2} \quad (5)$$

At $\delta=0$, and

$$x_3 x_3' - x_3^2 - R_3^2 = 0 \quad (6)$$

x_3' is expressed in terms of the other parameters and at any frequency

$Z_{03} =$

$$\frac{x_3^2 + R_3^2}{x_3} \left[\frac{R_3 x_3^2 + R_3^2}{x_3 (1+\delta)^2} + i \left[\frac{x_3^2 + R_3^2}{(1+\delta)} - \left(x_3^2 (1+\delta) + \frac{R_3^2}{1+\delta} \right) \right] \right] \quad (7)$$

$$R_3^2 + \left[x_3 (1+\delta) - \frac{x_3^2 + R_3^2}{x_3 (1+\delta)} \right]^2 \quad (7)$$

If, by definition

$$Q_3 = \frac{x_3}{R_3} \quad (8)$$

and it is assumed that $Q_3 \gg 1$, Equation 7 becomes, neglecting higher orders of δ

$$Z_{03} = \frac{x_3 (Q_3^2 + 1) \left\{ \frac{Q_3^2 + 1}{Q_3} - i\delta [2Q_3^2 + 1] [1 + \delta] \right\}}{4Q_3^4 \delta^2 + Q_3^2 (1 - 2\delta) + 1} \quad (9)$$

Then, since only the cases where $Q > 1$ and where $\delta \ll 1$ are of interest

$$Z_{03} = \frac{x_3 Q_3 [1 - 2i\delta Q_3]}{1 + 4Q_3^2 \delta^2} \quad (10)$$

and in Figure 3a

$$R_{03} = \frac{x_3 Q_3}{1 + 4Q_3^2 \delta^2}$$

$$x_{03} = -\frac{2x_3 Q_3^2 \delta}{1 + 4Q_3^2 \delta^2}$$

Another external resonator having a "Q" of Q_2 and impedance

$$Z_{02} = R_{02} + ix_{02} \quad (11)$$

is to be connected in parallel with the first resonator. The resulting parallel impedance is

$$Z_4 = \frac{Z_2 Z_3}{Z_2 + Z_3} = \frac{R_2 (R_2^2 + x_2^2) + R_2 (R_3^2 + x_3^2) + i[x_2 (R_3^2 + x_3^2) + x_3 (R_2^2 + x_2^2)]}{(R_2 + R_3)^2 + (x_2 + x_3)^2} \quad (12)$$

for the impedance branches, and

$$Z_5 = x_6 = \frac{x_2' x_2}{x_3' + x_2'} \quad (13)$$

for the reactance branches.

By definition

$$\frac{x_2}{R_2} = Q_2 \quad (14)$$

and

$$\frac{x_3}{R_3} = Q_3 \quad (15)$$

If

$$\frac{x_2}{R_2} > 1$$

and

$$\frac{x_3}{R_3} > 1 \quad (16)$$

then Equation 13 reduces to

$$Z_5 = x_6 = -\frac{x_3 x_2}{x_3 + x_2} \quad (17)$$

to a very close degree of approximation. Actually then the single equivalent parallel circuit is obtained by connecting Z_4 and Z_5 in parallel. However, since x_3' and x_2' have been taken as pure imaginaries, the Q of the resultant equivalent circuit is determined only by Z_4 with its associated Q_4 .

From (14)

$$\frac{x_2^2 + R_2^2}{R_2^2} = Q_2^2 + 1 \quad (18)$$

and from (15)

$$\frac{x_3^2 + R_3^2}{R_3^2} = Q_3^2 + 1 \quad (19)$$

Let m^2 be a factor relating $x_2^2 + R_2^2$ and $x_3^2 + R_3^2$, so that

$$m^2 (x_2^2 + R_2^2) = x_3^2 + R_3^2 \quad (20)$$

The quantity $\sqrt{x_2^2 + R_2^2}$ is the impedance associated with the external control resonator, and $\sqrt{x_3^2 + R_3^2}$ is the impedance associated with the oscillator.

From Equations 18, 19, and 20

$$\frac{R_2^2 m^2}{R_3^2} = \frac{Q_3^2 + 1}{Q_2^2 + 1} \quad \text{or} \quad R_2 = \frac{R_3}{m} \sqrt{\frac{Q_3^2 + 1}{Q_2^2 + 1}} \quad (21)$$

From Equation 21 and Equation 14

$$x_2 = R_2 Q_2 = \frac{R_3 Q_2}{m} \sqrt{\frac{Q_3^2 + 1}{Q_2^2 + 1}} \quad (22)$$

From Equation 12 and Equation 20

$$Z_4 = \frac{[R_2^2 + x_2^2][(R_3 + m^2 R_2) + i(x_3 + m^2 x_2)]}{(R_2 + R_3)^2 + (x_2 + x_3)^2} \quad (23)$$

and by definition the equivalent Q associated with Z_4 is

$$Q_4 = \frac{x_3 + m^2 x_2}{R_3 + m^2 R_2} \quad (24)$$

which is the Q resulting when circuits of Q_2 and Q_3 are connected in parallel.

From Equation 15, Equation 21, Equation 22 and Equation 24,

$$Q_4 = \frac{Q_3 + m Q_2 \sqrt{\frac{Q_3^2 + 1}{Q_2^2 + 1}}}{1 + m \sqrt{\frac{Q_3^2 + 1}{Q_2^2 + 1}}} \quad (25)$$

For any stabilizing work of interest $Q_3 \gg 1$. Also, unfortunately, $Q_3 \gg 1$. For this situation Equation 25 reduces to

$$Q_4 = \frac{Q_3 (1 + m)}{1 + \frac{Q_3 m}{Q_2}} \quad (26)$$

If P is a number relating Q_3 and Q_2 so that

$$P = \frac{Q_2}{Q_3} \quad (27)$$

that is, P is the ratio of the control Q to the oscillator Q, then Equation 26 reduces to

$$Q_4 = \frac{Q_3 (1 + m)}{1 + \frac{m}{P}} \quad (28)$$

and also

$$Q_4 = Q_2 \frac{m+1}{m+p} \quad (29)$$

The parallel impedance obtained by paralleling Z_4 and Z_5 is

$$Z_{4-5} = -i \frac{\frac{Z_2 Z_3}{Z_2 + Z_3} \frac{x_3 x_2}{x_3 + x_2}}{\frac{Z_2 Z_3}{Z_2 + Z_3} - i \frac{x_3 x_2}{x_3 + x_2}} \quad (30)$$

in which $Z_2 = R_2 + ix_2$ and $Z_3 = R_3 + ix_3$. The reactances x_2 and x_3 are functions of frequency, f . As is always the case, the resonant resistance of Z_{4-5} is

$$R_{4-5} = kP \left[\frac{x_2 (R_3^2 + x_3^2) + x_3 (R_2^2 + x_2^2)}{2\pi f [(R_2^2 + R_3^2)^2 + (x_2 + x_3)^2]} \right] \frac{1}{\frac{2\pi f}{x_3 x_2}}$$

or

$$R_{4-5} = kF \left\{ \frac{x_2(R_3^2 + x_3^2) + x_3(R_2^2 + x_2^2)}{(R_2^2 + R_3^2)^2 + (x_2 + x_3)^2} \cdot \frac{x_3 x_2}{x_3 + x_2} \right\} \quad (31)$$

Therefore this "parallel resonator" type of control will not be very satisfactory in most cases. The external resonator Q which is Q_2 , will be that obtained from a good cavity and may, for example, be about 5000. If it is assumed that there is very little external loading on the external resonator and slight loading on the oscillator resonator other than electronic loading of the cavity, then the factor m is almost certain to be less than unity since the oscillator resonator must have a lower Q than the external resonator. Probably the best that may be hoped for is the condition

$$m=1 \quad (32)$$

Using this result in Equation 28 and assuming that it is possible to build an external control cavity such that

$$P = \frac{Q_2}{Q_3} = 10 \quad (33)$$

then the resultant Q will be

$$Q_4 = \frac{20Q_3}{11} \cong 2Q_3 \quad (34)$$

Apparently, therefore, the best result which can be obtained from such a simple arrangement is an improvement of about two to one.

Actually, when the practical case is considered which involves power dissipation in a terminal impedance, the situation is even less favorable. The increased frequency stability indicated in Equation 28 is obtained by attaching an external high Q resonator. It is likely that the parallel resonant resistance of the combination will be very high. The external load must be transformed to a high value to avoid excessive shunting of the resonators. This in itself is not too easy to accomplish at the higher frequencies. In addition the overall high impedance circuit will be shunted excessively by stray impedances which are almost always present in any circuit.

METHOD II—RESONATORS PARALLEL-COUPLED THROUGH A TRANSFORMER

The first of these methods might logically be the addition of the same high Q external resonator, but with the addition of an "impedance inverting" or transforming line $n\pi + \pi/2$ long.

As before, let the impedance of the external resonator be

$$Z_{02} = R_{02} + ix_{02}$$

with a Q of $Q=Q_2$.

This impedance will be transformed by a line $n\pi + \pi/2$ in length to

$$Z_2' = \frac{Z_k^2(R_{02} - ix_{02})}{R_{02}^2 + x_{02}^2} \quad (35)$$

where Z_k is the "characteristic impedance" of the section of transforming line. It is convenient to write

$$\frac{Z^2 k}{R_{02}^2 + x_{02}^2} = \frac{1}{s} \quad (36)$$

where it is assumed that

$$s > 1 \quad (37)$$

The resultant Q and impedance of this "transformed" resonator connected in parallel with the oscillator resonator can be expressed easily. Let the parallel impedance be $Z_4' = R_4' + ix_4'$ and the parallel Q be Q_4' . It is convenient to use Figure

3 again as the equivalent except that x_3 , R_3 , and x_3' becomes x_2' , R_2' , and x_2'' respectively where

$$x_2' = \frac{x_2}{s} \text{ and } R_2' = \frac{R_2}{s}$$

As before, if

$$\frac{x_2'}{R_2'} > > 1$$

then $x_2' \cong -x_2''$. If Z_4' is composed of Z_2' and Z_3 in parallel, then

$$Z_4' = \frac{R_3[(R_2')^2 + (x_2')^2] + R_2(R_3^2 + x_3^2) + i[x_3(R_2')^2 + (x_2')^2] - x_2'(R_3^2 + x_3^2)}{(R_2' + R_3)^2 + (x_3 - x_2')^2} \quad (38)$$

which is quite similar to Equation 12 and

$$x_4' = \frac{x_3[(R_2')^2 + (x_2')^2] - x_2'(R_3^2 + x_3^2)}{(R_2' + R_3)^2 + (x_3 - x_2')^2} \quad (39)$$

By definition Q_4' is defined as

$$Q_4' = \frac{x_4'}{R_4'} \quad (40)$$

and from Equation 39

$$Q_4' = \frac{x_3[(R_2')^2 + (x_2')^2] - x_2'(R_3^2 + x_3^2)}{R_3[(R_2')^2 + (x_2')^2] + R_2'(R_3^2 + x_3^2)} \quad (41)$$

$$Q_4' = \frac{msQ_2\sqrt{\frac{Q_3^2+1}{Q_2^2+1}} - Q_3}{ms\sqrt{\frac{Q_3^2+1}{Q_2^2+1}} + 1} \quad (42)$$

which reduces for $Q_2 >> 1$ and $Q_3 >> 1$ to

$$Q_4' = Q_3 \frac{ms - 1}{1 + \frac{ms}{P}} \quad (43)$$

If, as before in Equation 32 and Equation 33, it is assumed that $m=1$ is the best obtainable value, $P=10$, and that it is possible to make $s=10$ then, from Equation 43

$$Q_5' = \frac{9Q_3}{2} \quad (44)$$

This represents an improvement of $4\frac{1}{2}:1$ as compared to the original improvement of about 2:1. The circuit will have lower impedance values than the "untransformed" version of Method I, so that unavoidable shunt impedances will be less objectionable, and the load impedance transformation will be less difficult since the required ratio is lower.

METHOD III—CONTROL IMPEDANCE TRANSFORMED, RESONATED AND SHUNT-CONNECTED TO GENERATOR

By resorting to an entirely different circuit principle of frequency stabilization much greater improvement is obtainable. The basic circuit of the instant invention is shown in Figure 4. The impedance Z_1 will be the parallel impedance of the two branches in the plane A—A. The lines are of length L_1 and L_2 and may be either wave guides, transmission lines, artificial lines, or equivalent circuits containing mutual reactances and impedances.

Referring to Figure 4, it is convenient to let the "characteristic impedances" of lines L and L_1 be alike and represented by Z_k , and the propagation constant $P=\alpha+i\beta$.

Actually, of course, the lines will have some attenuation so that transmission equations will in general have exponential attenuating factors, and the line equations may be written conveniently with the use of the usual hyperbolic functions. However, to simplify the expressions greatly, it may be assumed that the distributed series resistance of the line per unit length approaches zero and the distributed shunt resist-

ance of the line per unit length approaches infinity. Thus the hyperbolic functions may be replaced by their corresponding trigonometric functions. Accordingly, the impedance Z_1 in the plane A—A is

$$Z_1 = Z_k \frac{\frac{R+ix}{Z_k} \cos \beta L + i \sin \beta L \frac{R_6+ix_6}{Z_k} \cos \beta L_1 + i \sin \beta L_1}{\cos \beta L + i \frac{R+ix}{Z_k} \sin \beta L \cos \beta L_1 + \frac{R_6+ix_6}{Z_k} \sin \beta L_1} \quad (45)$$

$$Z_1 = Z_k \frac{\frac{R+ix}{Z_k} \cos \beta L + i \sin \beta L \frac{R_6+ix_6}{Z_k} \cos \beta L_1 + i \sin \beta L_1}{\cos \beta L + i \frac{R+ix}{Z_k} \sin \beta L \cos \beta L_1 + \frac{R_6+ix_6}{Z_k} \sin \beta L_1}$$

Rationalizing, an exceedingly cumbersome expression for Z_1 is obtained, which may be written in simplified form

$$Z_1 = \rho + i\rho' \quad (45a)$$

in which ρ and ρ' are each functions of R , x , R_6 , x_6 , Z_k , βL , and βL_1 .

The various circuit constants must be selected and related so that the maximum rate of phase change with frequency in Z_1 at A—A is obtained. This may be accomplished by making

$$\frac{\partial^2 \left(\frac{\rho'}{\rho} \right)}{\partial R^2} = 0 \text{ for a maximum} \quad (46a)$$

$$\frac{\partial^2 \left(\frac{\rho'}{\rho} \right)}{\partial x^2} = 0 \quad (46b)$$

$$\frac{\partial^2 \left(\frac{\rho'}{\rho} \right)}{\partial R_6^2} = 0 \quad (46c)$$

$$\frac{\partial^2 \left(\frac{\rho'}{\rho} \right)}{\partial x_6^2} = 0 \quad (46d)$$

$$\frac{\partial^2 \left(\frac{\rho'}{\rho} \right)}{\partial (\beta L)^2} = 0 \quad (46e)$$

$$\frac{\partial^2 \left(\frac{\rho'}{\rho} \right)}{\partial (\beta L_1)^2} = 0 \quad (46f)$$

where x and x_6 are functions of frequency, and R is practically independent of frequency for small frequency changes Δf near f , but it is apparent that the solution of the simultaneous Equations 46 is impractical. However, consideration of the desired result in view of the circuit of Fig. 4 permits certain assumptions to be made which simplify the solution.

In Figure 4 let $L=0$, and let R be the load resistance directly, (or some transformed load resistance). By connecting in series with R a reactance x which is a function of frequency, one element of a parallel (referred to a plane through A—A) resonant circuit is provided. The other element is R_6+ix_6 . For maximum rate of phase change with frequency at A—A, impedance $R+ix$ and R_6+ix_6 should have the highest possible Q values. By using a shorted section of low attenuation line it is seen that

$$R_6 \rightarrow 0 \quad Z_6 = ix_6 \quad (47)$$

The branch Z contains the load resistance R which limits the upper value for x since, if x is too large, the resonant resistance at A—A will be

too high. The attendant difficulties for a high resonant resistance have already been discussed. The result is that the Q of the branch $R+ix$ will be limited quite severely.

5 If a line length L is selected which will trans-

form the impedance $Z=R+ix$ to $Z_t=R_t+ix_t$ in which

$$\left. \begin{aligned} \frac{x_t}{R_t} &> \frac{x}{R} \\ R^2 + x^2 &> R_t^2 + x_t^2 \end{aligned} \right\} \quad (48)$$

the impedance $|Z|$ can be transformed to a smaller numerical value $|Z_t|$ and at the same time the ratio

$$\left| \frac{x}{R} \right|$$

is transformed to a larger ratio

$$\left| \frac{x_t}{R_t} \right|$$

This feature is very important.

At the plane A—A, looking to the left, the impedance Z_t is

$$Z_t = Z_k \frac{\frac{R+ix}{Z_k} \cos \beta L + i \sin \beta L}{\cos \beta L + i \frac{R+ix}{Z_k} \sin \beta L}$$

which reduces to a more convenient form

$$Z_t = Z_k \frac{\frac{R}{Z_k} + i \frac{x}{Z_k} \cos 2\beta L + \left[1 - \left(\frac{x}{Z_k} \right)^2 - \left(\frac{R}{Z_k} \right)^2 \right] \sin 2\beta L}{\frac{1}{2} \left[1 + \left(\frac{x}{Z_k} \right)^2 + \left(\frac{R}{Z_k} \right)^2 \right] - \frac{x}{Z_k} \sin 2\beta L + \left[1 - \left(\frac{x}{Z_k} \right)^2 - \left(\frac{R}{Z_k} \right)^2 \right] \cos 2\beta L} \quad (49)$$

50 Instead of the inequalities of (48) it is convenient to write

$$t = \frac{R_t}{x} \quad (50)$$

where

$$T > 1, \frac{x_t}{R_t} > 1, \text{ and } \frac{x_t}{R_t} > 1$$

60 Thus t is the Q ratio of the transformed impedance to the untransformed impedance.

$$U^2 = \frac{R^2 + x^2}{R_t^2 + x_t^2} \quad (51)$$

65 where $U > 1$. The product U_t may be maximized where the line length βL will become the variable.

Considering frequency changes of the form

$$f = f_0(1+\delta)$$

70 where f_0 is the initial frequency, δ may be either positive or negative, and $\delta < 1$. Then

$$\frac{x^2}{R^2} = Q^2 \quad (52)$$

and

$$\frac{x_t^2}{R_t^2} = Q_t^2 \quad (53)$$

$$x^2 + R^2 = R^2(Q^2 + 1) \quad (54)$$

and

$$xt^2 + R_t^2 = R_t^2(Qt^2 + 1) \quad (55)$$

Using Equations 54 and 55 in 51, it is seen that

$$U = \frac{R}{R_t} \sqrt{\frac{Q^2 + 1}{Q_t^2 + 1}} \quad (56)$$

$$U = \frac{R}{R_t} \frac{Q}{Q_t} = \frac{x}{x_t} \quad (56)$$

and if $Q \gg 1$, $Qt \gg 1$

$$R_t^2 = \frac{R^2}{U^2 t^2} \quad (57)$$

From Equation 56

$$x_t^2 = \frac{x^2}{U^2} \quad (58)$$

Since

$$|Z_t|^2 = x_t^2 + R_t^2$$

then

$$|Z_t|^2 = \frac{1}{U^2} \left[\frac{R^2}{t^2} + x^2 \right] \quad (59)$$

Since it is desirable to make the inequalities of (48) as great as possible, it follows that the conditions which make the product Ut a maximum are desirable. The conditions which make U and t reach their maximum values independently should be checked to be sure that the required conditions are not opposing.

From Equations 56 and 50

$$Ut = \frac{R}{R_t} \quad (60)$$

From Equations 60 and 49

$$Ut = \frac{1}{2} \left\{ 1 - \frac{2x \sin 2\beta L}{Z_k} + \left(\frac{x}{Z_k} \right)^2 + \left(\frac{R}{Z_k} \right)^2 + \left[1 - \left(\frac{x}{Z_k} \right)^2 - \left(\frac{R}{Z_k} \right)^2 \right] \cos 2\beta L \right\} \quad (61)$$

$$\frac{\partial(Ut)}{\partial \beta L} = \left\{ -\frac{2x}{Z_k} - \left[1 - \left(\frac{x}{Z_k} \right)^2 - \left(\frac{R}{Z_k} \right)^2 \right] \tan 2\beta L \right\} \cos 2\beta L = 0 \quad (62)$$

The roots are

$$\cos 2\beta L = 0 \quad \beta L = \frac{\pi}{4}, \frac{3\pi}{4}, \dots, \frac{2n-1}{4}\pi \quad (63)$$

where n is any integer, and

$$\tan 2\beta L = -\frac{2x}{Z_k \left[1 - \left(\frac{x}{Z_k} \right)^2 - \left(\frac{R}{Z_k} \right)^2 \right]} \quad (64)$$

If a matched load condition is assumed for the terminal impedance

$$R = Z_k \text{ but } x \neq 0$$

Equation 64 reduces to

$$\tan 2\beta L = \frac{2Z_k}{x}$$

and to fulfill Equation 52

$$\frac{Z_k}{x} \rightarrow 0$$

$$\tan 2\beta L \rightarrow 0 \text{ and } \beta L = \frac{(2n-1)}{2}\pi \quad (65)$$

 n is any integer.

The conditions to be investigated occur, therefore, at

$$\begin{cases} \cos 2\beta L = 0 \\ \sin 2\beta L = 1 \end{cases} \quad (66)$$

$$\begin{cases} \cos 2\beta L = 0 \\ \sin 2\beta L = -1 \end{cases} \quad (67)$$

$$\begin{cases} \cos 2\beta L = 1 \\ \sin 2\beta L = 0 \end{cases} \quad (68)$$

and

$$\begin{cases} \cos 2\beta L = -1 \\ \sin 2\beta L = 0 \end{cases} \quad (69)$$

In each case R_t and x_t may be obtained by the use of Equation 49 and these quantities may be compared with R and x respectively. In each case assume

$$\begin{cases} R = Z_k \\ x > Z_k \end{cases} \quad (70)$$

Then for the first condition, Equation 66

$$Z_t = R_t + ix_t = \frac{2Z_k^3}{x^3} - iZ_k \quad (71)$$

or

$$R_t = \frac{2Z_k^3}{x^2}$$

and

$$x_t = -Z_k$$

The initial impedance Z was

$$Z = R + ix = Z_k + ix$$

so that the quantities U , t ,

$$Q = \frac{x}{R}$$

and

$$Q_t = \frac{x_t}{R_t}$$

may be compared

$$|U| = \frac{x}{x_t} = \frac{x}{Z_k} \quad (72)$$

$$|t| = \frac{x_t R}{R x} = \frac{x}{2Z_k} \quad (73)$$

$$Q = \frac{x}{R} = \frac{x}{Z_k} \quad (74)$$

$$Q_t = \frac{x_t}{R_t} = \frac{x^2}{2Z_k^2} \quad (75)$$

The interesting result is that

$$Q_t = \frac{Q^2}{2} \quad (76)$$

and at the same time

$$\sqrt{R_t^2 + x_t^2} = \sqrt{\frac{R^2 + x^2}{Q}}$$

It has been assumed that $Q \gg 1$, so if $Z = R + ix$ is parallel resonated with a reactance $x' \approx -x$ the resonant resistance is

$$R_{\text{res}} = xQ \quad (77)$$

while if

$$Z_t = \frac{2Z_k^3}{x^3} - iZ_k$$

is parallel resonated with a reactance $x' \approx -x_t$, the resonant resistance is

$$R_{\text{t res}} = x_t Q_t = \frac{xQ}{2} = \frac{R_{\text{res}}}{2} \quad (78)$$

It therefore appears that the initial Q has been increased to

$$\frac{Q^2}{2}$$

at the same time the parallel resonant resistance has been decreased from

$$R_{\text{res}} \text{ to } \frac{R_{\text{res}}}{2}$$

For the second condition of Equation 27

$$Z_t = R_t + ix_t = \frac{2Z_k^3}{x^2} + iZ_k \quad (79)$$

Correspondingly,

$$U = \frac{x}{x_t} = \frac{x}{Z_k} \quad (80)$$

$$t = \frac{x_t R}{R x} = \frac{x}{2Z_k} \quad (81)$$

$$Q = \frac{x}{R} = \frac{x}{Z_k} \quad (82)$$

$$Q_t = \frac{x_t}{R_t} = \frac{x^2}{2Z_k^2} = \frac{Q^2}{2} \quad (83)$$

$$\sqrt{R_t^2 + x_t^2} = \frac{\sqrt{R^2 + x^2}}{Q} \quad (84)$$

The initial ($Z=R+ix$ in parallel with $-ix$) resonant resistance is

$$R_{\text{res}} = \frac{xQ}{2} \quad (85a)$$

while the transformed parallel resonant resistance is

$$R_{t\text{res}} = \frac{xQ}{2} = \frac{R_{\text{res}}}{2} \quad (85b)$$

Apparently the only difference is that the reactance x_t changes sign.

For the third condition of Equation 63

$$Z_t = R_t + ix_t = Z_k + ix \quad (86)$$

and in similar fashion

$$U = \frac{x}{x_t} = 1 \quad (87)$$

$$t = \frac{x_t R}{R x} = 1 \quad (88)$$

$$Q = \frac{x}{R} = \frac{x}{Z_k} \quad (89)$$

$$Q_t = \frac{x_t}{R_t} = Q \quad (90)$$

$$\sqrt{R_t^2 + x_t^2} = \sqrt{R^2 + x^2} \quad (91)$$

For this condition nothing has been changed or gained by the transformation. For the fourth condition of Equation 69

$$Z_t = \frac{Z_k^3}{x^2} - \frac{iZ_k^2}{x} \quad (92)$$

Continuing as before

$$U = \frac{x}{x_t} = \frac{x^2}{Z_k^2} = Q^2 \quad (93)$$

$$t = \frac{x_t R}{R x} = 1 \quad (94)$$

$$Q = \frac{x}{R} = \frac{x}{Z_k} \quad (95)$$

$$Q_t = \frac{x_t}{R_t} = \frac{x}{Z_k} \quad (96)$$

or

$$Q_t = Q$$

$$\sqrt{R_t^2 + x_t^2} = \frac{\sqrt{R^2 + x^2}}{Q^2} \quad (98)$$

The initial ($Z=R+ix$ in parallel with $-ix$) resonant resistance is

$$R_{\text{res}} = xQ \quad (99)$$

while the transformed parallel resonant resistance is

$$R_{t\text{res}} = Z_k = \frac{R_{\text{res}}}{Q^2} \quad (100)$$

Therefore it may be concluded that the first two conditions are identical except for change of sign of the reactance x_t and both are very useful. Condition three is of no value and condition four must be compared with the first two.

The physical circuit configuration which will provide the arrangement of Figure 4 to the left of the plane A—A must be determined. This may be done with sections of transmission lines or with sections of wave guides having the necessary modifications. The circuit of Figure 5 will provide the arrangement of Figure 4 to the left of A—A. The circuit is composed of R , the shorted length of line L_2 and the line L . However, if the reactance x , where $x=Z_k \tan \beta L_2$, is large as compared to R , as is necessary, it will be difficult to deliver sufficient power to the resistance R . Therefore, it is convenient to substitute the circuit of Figure 6. The line L_2 initially is selected to be approximately $n\pi$ wavelengths long and the wavelength is varied from λ to $\lambda(1+\delta)$ where it is assumed that $\delta \ll 1$. Thus

$$\beta L_2 = n\pi + \phi \quad (101)$$

and βL_2 changes in the following manner

$$\beta L_2 = (n\pi + \phi)(1+\delta) \quad (102)$$

40 The resistance R_s , where $R_s \rightarrow 0$, is inserted to provide a decoupled resonator. The equivalent circuit, using sections of wave guides, is shown in Figure 7.

45 Accordingly, a rapid rate of reactance change in x with frequency is obtained. This condition will be as satisfactory as if $x \gg R$ and the difficulty in delivering power to R is avoided. In Figure 6 the effect of the discontinuity introduced by inserting R_s as shown must be determined. This may be done by referring to the auxiliary circuit of Figure 8. It may be shown that the resonator above R_s , but including R_s , in Figure 6 reduces to the circuit of Figure 9.

50 In similar fashion the effect of the cut-off window between L_2 and the resonator L_2 in Figure 7 also must be determined. It is useful to introduce the auxiliary circuit of Figure 10 for this purpose. It may be shown that the resonator above the cut-off window, but including the window, in Figure 7 reduces to the circuit of Figure 11.

55 Apparently it is not generally appreciated that the resonators of Figure 9 or Figure 11 when viewed from R_s or the cut-off coupling window respectively, or at a plane $n\pi$ removed may be made to operate either as series type or parallel type resonators.

60 In the waveguide case this is effected by choice of window size as compared to that window size which matches the resonator to the wave guide. This fact is especially important. For simplicity it may be assumed that the lines to the right of x_L in Figure 9 and to the right of window x_W in Figure 11 have no attenuation. Then for series type operation as viewed from Z_{R1} and Z_{R2} re-

spectively, x_L and cut-off guide $\beta_c L_c$, which is represented in Figure 11 by x_w , may be omitted for all practical purposes. At resonance in Figure 9 and Figure 11, βL_2 will always be $n\pi$. In both cases the resonators will display all the characteristics of series resonators, and at resonance the resonant resistance will be low and approach 0 as $R \rightarrow 0$.

In many cases it is desirable to have Z_L and Z_w in Figures 9 and 11 respectively, exhibit the characteristics of parallel resonators with their characteristic high resonant resistance. This may be done as follows:

In Figure 8 a line of characteristic impedance Z_k is shunted with a resistance $R_s \rightarrow 0$, and the termination Z_k is provided, as shown. Then,

$$Z_L = Z_k \frac{\frac{R_s}{Z_k + R_s} (1 + \tan^2 \psi) + i \tan \psi \left[1 - \left(\frac{R_s}{Z_k + R_s} \right)^2 \right]}{1 + \left(\frac{R_s}{Z_k + R_s} \right)^2 \tan^2 \psi} \quad (103)$$

which for $R_s \rightarrow 0$ reduces to

$$Z_L = Z_k \frac{\frac{R_s}{Z_k} + 1 \psi}{1 + \left(\frac{R_s}{Z_k} \psi \right)^2} = Z_k \left[\frac{R_s}{Z_k} + i \psi \right] \quad (104)$$

Disregarding the real part of Equation 104, since that it is a term which will affect only the Q , the discontinuity provided by R_s is equivalent to the reactance $i x_L$ in Figure 9.

The reason for introducing ϕ in Equation 101 is apparent. If ϕ is large enough so that the input reactance of βL_2 is negative, the arrangement of Figure 9 is obtained where $i x_L$ and the negative reactance of line βL_2 , which is $i Z_k \tan \beta L_2$, are parallel resonated. The line βL_2 is never $n\pi$ at resonance, but instead is always in the second or fourth quadrants. The impedance Z_{R1} in Figure 9 accordingly may be a large resistance at resonance and has all the characteristics of a parallel resonator when viewed $n\pi$ to the left of x_L .

The same situation exists when wave guides are used with a thin cut-off window. In Figure 10 a thin section of cut-off guide is terminated in a section of guide of characteristic impedance Z_k which is terminated in turn by Z_k . In this case the propagation constant of the section cut-off guide is

$$\gamma = i \frac{2\pi}{\lambda_0} \sqrt{1 - \left(\frac{\lambda_0}{2a} \right)^2} \quad (105)$$

where λ_0 is the free space wavelength and a is the width of the guide. As usual, beyond cut-off

$$\frac{\lambda_0}{2a} > 1$$

so that Equation 105 becomes

$$\gamma = -i \frac{2\pi}{\lambda_0} \sqrt{\left(\frac{\lambda_0}{2a} \right)^2 - 1} = -\beta_c \quad (106)$$

The "characteristic impedance" of the section

$$Z_{R1} = i Z_k \frac{\frac{a R_s}{Z_k} \left[\cos^2 \left(n\pi - \frac{n\pi\delta}{1+\delta} \right) + \sin^2 \left(\frac{n\pi\delta}{1+\delta} \right) \right] + i \sin \left(\frac{n\pi\delta}{1+\delta} \right) \cos \left(n\pi - \frac{n\pi\delta}{1+\delta} \right) \left[\left(\frac{a R_s}{Z_k} \right)^2 - 1 \right]}{\cos^2 \left(n\pi - \frac{n\pi\delta}{1+\delta} \right) + \left[\frac{a R_s}{Z_k} \sin \left(\frac{n\pi\delta}{1+\delta} \right) \right]^2} \quad (114)$$

And when Z_{R1} is connected in parallel with R_s ,

$$Z' = \frac{R_s Z_k \left[\frac{a R_s}{Z_k} \left[\cos^2 \left(n\pi - \frac{n\pi\delta}{1+\delta} \right) + \sin^2 \left(\frac{n\pi\delta}{1+\delta} \right) \right] + i \sin \left(\frac{n\pi\delta}{1+\delta} \right) \cos \left(n\pi - \frac{n\pi\delta}{1+\delta} \right) \left[\left(\frac{a R_s}{Z_k} \right)^2 - 1 \right] \right]}{(1+a) R_s \cos^2 \left(n\pi - \frac{n\pi\delta}{1+\delta} \right) + R_s \left[\frac{a R_s}{Z_k} \sin \left(\frac{n\pi\delta}{1+\delta} \right) \right]^2 + a R_s \sin \left(\frac{n\pi\delta}{1+\delta} \right) + i Z_k \sin \left(\frac{n\pi\delta}{1+\delta} \right) \cos \left(n\pi - \frac{n\pi\delta}{1+\delta} \right) \left[\left(\frac{a R_s}{Z_k} \right)^2 - 1 \right]} \quad (115)$$

of cut-off guide Z_k must be a negative imaginary so that

$$Z_k = -i \mu Z_k \quad (107)$$

Then, the input impedance of the thin section of cut-off guide which is terminated in Z_k is

$$Z_w = Z_k \frac{\frac{Z_k}{Z_{kc}} \cosh(\beta_c L_c) - \sinh(\beta_c L_c)}{\cosh(\beta_c L_c) - \frac{Z_k}{Z_{kc}} \sinh(\beta_c L_c)} \quad (108)$$

which reduces to

$$Z_w = Z_k \frac{1 - \tanh^2(\beta_c L_c) + i \left(\mu + \frac{1}{\mu} \right) \tanh(\beta_c L_c)}{1 + \frac{\tanh^2(\beta_c L_c)}{\mu^2}} \quad (109)$$

and for $\beta_c L_c$ small

$$Z_w = Z_k \frac{1 - (\beta_c L_c)^2 + i \left(\mu + \frac{1}{\mu} \right) (\beta_c L_c)}{1 + \left(\frac{\beta_c L_c}{\mu} \right)^2} \quad (110)$$

For the special case where $\beta_c L_c \ll 1$,

$$Z_w = 1 + i \left(\mu + \frac{1}{\mu} \right) \beta_c L_c \quad (111)$$

so that it appears that the thin cut-off section of wave guide serves as a lumped reactance $i x_w$, which is

$$i x_w = i \left(\mu + \frac{1}{\mu} \right) \beta_c L_c \quad (112)$$

Again in Equation 101 the value of ϕ is chosen so that βL_2 in Figure 11 is in the second or fourth quadrant. The reactance $i x_w$ is resonated with the negative reactance $Z_k \tan \beta L_2$ at the desired frequency. The resonant resistance is a function of

$$\frac{x_w}{Z_k \tan \beta L_2}$$

and increases with increasing

$$\frac{x_w}{Z_k \tan \beta L_2}$$

At any one frequency the magnitude of the parallel resonance resistance is controlled by proper choice of μ , β_c , L_c , and βL_2 . Again at resonance $\beta L_2 \neq n\pi$.

Since, for some applications, it may be advantageous to operate the resonators of Figures 9 and 11 as series resonators, the conditions for this operation must be determined. The right hand termination in each case becomes $R \rightarrow 0$.

The impedance Z_{R1} must be determined. This time the line is $n\pi$ long initially at resonance, and changes from $n\pi$ to $n\pi(1+\delta)$ as the wavelength in the guide is changed. Again $R_s \ll 1$, and

$$\frac{n\pi}{1+\delta} = n\pi - \frac{n\pi\delta}{1+\delta} \quad (113)$$

Then

For the symmetrical case $a=1$, and n even, Equation 115 reduces to

$$Z' = \frac{R_s}{2} \frac{1-iZ_k n \pi \delta}{1 + \left[\frac{Z_k n \pi \delta}{2R_s(1+\delta)} \right]^2} \quad (116)$$

and is for $\delta \ll 1$

$$Z' = \frac{R_s}{2} \frac{1-iZ_k n \pi \delta}{1 + \left[\frac{Z_k n \pi \delta}{2R_s} \right]^2} \quad (117)$$

As would be expected Z' has the characteristic form of impedance variation of a resonator, as is seen from comparison of Equation 117 with Equation 10. If line L_2 is considered to be the resonator and if the equivalent Q is expressed as

$$Q = \frac{Z_k n \pi}{4R_s} \quad (118)$$

then Equation 105 converts to the characteristic form

$$Z' = \frac{R_s}{2} \frac{1-i2Q\delta}{1+4Q\delta^2} \quad (119)$$

and the phase change of Z' with frequency is proportional to Q , as would be expected.

Similarly, for Figure 11, βL_2 will be $n\pi$ at resonance and change to $n\pi(1+\delta)$ with changes in wavelength in the guide. The termination for the thin cut-off guide is

$$Z_s = Z_k \frac{b+i \tan[n\pi(1+\delta)]}{1+ib \tan[n\pi(1+\delta)]} \quad (120)$$

or

$$Z_s = \frac{b\{1+\tan[n\pi(1+\delta)]\}+i(1-b^2)\tan[n\pi(1+\delta)]}{1+b^2\tan^2[n\pi(1+\delta)]}$$

or $Z_s = C+iD$ where

$$C = \frac{b(1+\tan[n\pi(1+\delta)])}{1+b^2\tan^2[n\pi(1+\delta)]} \quad (121)$$

$$D = \frac{(1-b^2)\tan[n\pi(1+\delta)]}{1+b^2\tan^2[n\pi(1+\delta)]} \quad (122)$$

$$Z_{k2} = Z_k \frac{\frac{C}{\mu Z_k} \cos(2\beta_c L_c) + \left[1 + \frac{(D^2 - C^2)}{(\mu Z_k)^2} \right] \frac{\sin(2\beta_c L_c)}{2} + i \left[\frac{D \cos(2\beta_c L_c)}{(\mu Z_k)} - \frac{CD \sin(2\beta_c L_c)}{(\mu Z_k)^2} \right]}{\frac{1}{2} + \frac{\cos(2\beta_c L_c)}{\mu Z_k} - \frac{C \sin(2\beta_c L_c)}{\mu Z_k} + \frac{i - \cos(2\beta_c L_c)}{2(\mu Z_k)^2} (C^2 + D^2)} \quad (123)$$

Since the impedance change near resonance is to be used for frequency control purposes, it is desirable to operate the cavity resonator near cut-off. Accordingly, the change in wavelength in a rectangular guide (also used as a resonator in this application because of convenience) λ_g , either with frequency or its inverse λ_0 , the free space wavelength is important.

The guide has cross section ab and $a>b$. The wavelength in the guide is

$$\lambda_g = \frac{\lambda_0}{\sqrt{1 - \left(\frac{\lambda_0}{2a} \right)^2}} \quad (124)$$

Then

$$\frac{d\lambda_g}{d\lambda_0} = \frac{1 - \left(\frac{\lambda_0}{2a} \right)^2 + \left(\frac{\lambda_0}{2a} \right)^2}{1 - \left(\frac{\lambda_0}{2a} \right)^2} \quad (125)$$

or

$$d\lambda_g = \frac{d\lambda_0}{\left[1 - \left(\frac{\lambda_0}{2a} \right)^2 \right]^{3/2}}$$

For standard X-band guide $2a=1.80$ inches and at 9310 megacycles per second $\lambda_0=1.27$ inches, so that

$$d\lambda_g = 2.82 d\lambda_0 \quad (126)$$

which indicates that the rate of change of wavelength in the guide is 2.82 times the rate of change of frequency. The factor 2.82 would, of course, be greater by operating nearer cut-off.

Considering the circuit of Figure 7 with the T junction shown in Figure 12, under conditions wherein

$$a > \frac{\lambda_0}{2}$$

where λ_0 is the free space wavelength, $b < a$, and the special case where $c=b$.

Y_1 is the normalized admittance extrapolated to $Z=0$ for the left leg, $Z < 0$, Y_3 is the normalized admittance extrapolated to $Z=0$ for the right leg, $Z > 0$.

Y_2 is the normalized admittance extrapolated to $y=b$ for the vertical leg, $y > b$.

$Y_1 = Y_3 = 1$ for a travelling wave propagated in the $+Z$ direction.

$Y_1 = Y_3 = -1$ for a travelling wave propagated in the $-Z$ direction.

For the circuit configuration of Figure 6, Y_1 , Y_2 , and Y_3 are related by the following two equations:

$$Y_1 = \frac{1+a_2(-a_1+i a_3 Y_2) Y_3 + 2(i a_1 + a_3 Y_2)}{1+a_2(-a_1+i a_3 Y_2 + i 2 Y_3)} \quad (127)$$

$$Y_3 = \frac{[1+a_2(-a_1+i a_3 Y_2)] Y_1 - 2(i a_1 + a_3 Y_2)}{1+a_2(-a_1+i a_3 Y_2 - 2i Y_1)} \quad (128)$$

where a_1 , a_2 and a_3 are real positive numbers which are functions of b/λ_g and c/b , where λ_g is the wavelength of the longest TE wave propagated in the guide. For this case assume $b=c$.

Then $a_1 = .368$, $a_2 = 10.4$, and $a_3 = 2.49$ for a standard X-band wave guide.

Considering the case where wave propagation is from the left, where the vertical branch has an admittance Y_2 , and where the right hand branch has a matched termination,

$$Y_3 = 1 \quad (129)$$

and Equation 128 becomes

$$Y_3 =$$

$$60 \quad 63 \quad \frac{[1+10.4(-.368+i2.49Y_2)] Y_1 - 2(i.368+2.49Y_2)}{1+10.4(-.368+i2.49Y_2-2iY_1)} = 1 \quad (130)$$

or

$$70 \quad 71 \quad Y_1 = \frac{-2.82 + 4.98Y_2 + i(25.9Y_2 + .735)}{-2.82 + i(25.9Y_2 + 20.8)} \quad (131)$$

It is sometimes easier to use a rationalized form of Equation 131. If Y_2 is of the form

$$75 \quad 76 \quad Y_2 = y(\cos \theta + i \sin \theta) \quad (132)$$

$$Y_1 = \frac{23.25 + 249.8y \sin \theta + 544y \cos \theta + 671y^2 + i(56.52 + 505y \sin \theta - 103.8y \cos \theta - 129y^2)}{438.9 + 146y \sin \theta + 1080y \cos \theta + 671y^2} \quad (133)$$

In Figure 7 the resonant resistance of the resonator may be expressed in terms of the characteristic impedance of the line L_3 and may be considered as a termination for L_3 . The impedance of the resonator off resonance as a termination for L_3 should be considered to determine the rate of change of phase angle and reactance with frequency. It is convenient to consider the resonant resistance and impedance values $\frac{1}{2}Q$ above and below the resonant frequency. The resonant resistance is $a_0 Z_k$ where Z_k is the characteristic impedance of L_3 and $a_0 Z_k$ is either greater than, or less than Z_k , as has been shown. The impedance at a frequency $\frac{1}{2}Q$ higher than the resonant frequency will be

$$\frac{a_0 Z_k}{2}(1-i)$$

and the impedance at a frequency $\frac{1}{2}Q$ lower than the resonant frequency will be

$$\frac{a_0 Z_k}{2}(1+i)$$

To complete the frequency control circuit of Figure 4, it is only necessary to consider various terminations for L_3 in Figure 7 which involve various values of a_0 , and the transforming action of L_3 . This terminating admittance is the Y_2 of Equation 131. The admittance Y_1 is then the termination for line L in Figure 4. Line L transforms Y_1 to a new admittance at the plane A—A. The corresponding impedance at A—A is then parallel resonated with the reactance provided by line L_1 .

This final resonator is then connected directly to the oscillator, or to the oscillator through a coupling line or circuit.

It is necessary first to determine the line length L_3 in Figure 7 which will give maximum rate of phase change at the junction with line L , all for a change in phase at the resonator, which is then the termination for L_3 . The resonator termination in terms of Z_k is $a_0 Z_k$. At resonance a_0 is a real positive number, and off resonance it is complex with a positive real part, so that

$$a_0 = a_1 + ia_2 \quad (134)$$

Accordingly, the normalized input impedance of line L_3 as viewed from line L is

$$Z_c = \frac{a_1(1 + \tan^2 \beta L_3) + i[a_2(1 - \tan^2 \beta L_3) + (1 - a_1^2 - a_2^2) \tan \beta L_3]}{1 - 2a_2 \tan \beta L_3 + (a_1^2 + a_2^2) \tan \beta L_3} \quad (135)$$

and the phase angle is measured by

$$P = k \frac{a_2(1 - \tan^2 \beta L_3) + (1 - a_1^2 - a_2^2) \tan \beta L_3}{a_1(1 + \tan^2 \beta L_3)} \quad (136)$$

$$\frac{1}{Z_c}$$

in Equation 135 is the Y_2 of Equation 131.

Rewriting Equation 136

$$P = k \frac{a_2(\cos^2 \beta L_3 - \sin^2 \beta L_3) + (1 - a_1^2 - a_2^2) \sin \beta L_3 \cos \beta L_3}{a_1} \quad (136)$$

or

$$P = k \frac{a_2 \cos^2 \beta L_3 + \frac{1 - a_1^2 - a_2^2}{2} \sin \beta L_3}{a_1} \quad (137)$$

To obtain the maximum rate of change of P with βL_3 and a_2

$$\frac{\partial^2 P}{\partial \beta L_3^2} =$$

$$\frac{k}{a_1} [-2(1 - a_1^2 - a_2^2) \sin 2\beta L_3 - 4a_2 \cos 2\beta L_3] = 0 \quad (138)$$

and

$$\frac{\partial^2 P}{\partial a_2^2} = \frac{k}{a_1} [-2a_2 \cos 2\beta L_3 - \sin 2\beta L_3] = 0 \quad (139)$$

The region where a_2 is zero initially and then assumes small positive and negative values is of primary interest. Equations 138 and 139 give

$$\beta L_3 = 0, \pi/2, \pi, \dots \quad (140)$$

Obviously, from Equations 140, 135 and 131, if Y_1 in Equation 131 is to undergo maximum rate of phase change with small changes in a_2 , from zero, there are two choices for βL_3 .

1. If the resonator termination on L_3 (Figure 7) operates as a parallel resonant circuit $a_0 > 1$ and $L_2 = n\pi$

$$\beta L_3 = 0, \pi, 2\pi, \dots, n\pi \quad (141)$$

2. If the resonator termination on L_3 (Figure 7) operates as a series resonant circuit $a_0 < 1$ and $L_2 = n\pi$ initially, then from Equation 140

$$\beta L_3 = \frac{\pi}{2}, \frac{3\pi}{2}, \dots, \frac{2n-1}{2}\pi \quad (142)$$

Condition 1 is preferred since the high ratio, and necessarily low attenuation

$$\frac{2n-1}{2}\pi$$

line transformer which is automatically incorporated in condition 2 is avoided. However, if extreme care is taken to make the

$$\frac{2n-1}{2}\pi$$

line transformer very low loss, condition 2 is also capable of providing good results. Since condition 1 is the preferred condition, it may be assumed that in Figure 7

$$\beta L_2 \text{ (at resonance)} \neq n\pi, \beta L_3 = n\pi$$

but it should be understood that the alternative condition

$$\beta L_2 \text{ (at resonance)} = n\pi, \beta L_3 = \frac{2n-1}{2}\pi$$

may be substituted, although the results then are likely to be poorer mainly because of the difficulty in making the

$$\frac{2n-1}{2}\pi$$

transformer good enough.

All that remains is to determine line length L in Figure 4. Equations 66, 67, 68, and 69 which result in Equations 76, 77, 83, 84, 90, 91, 97, and 98 indicates that βL should be either

$$\beta L = \frac{2n-1}{2}\pi \quad \text{or} \quad \beta L = \frac{2n-1}{4}\pi$$

The better condition may be determined. For 70 various resonator terminations $a_0 Z_k$ for line L_2 , where $a_0 > 1$, $\beta L_2 = n\pi$. Equations 131 or 132 provide the values of Y_1 for the various indicated conditions of Table I. Conditions at resonance and off resonance by $\pm \frac{1}{2}Q$ in frequency are 75 shown.

5.0 (1-i)	.909 - i. 323	.965 / -19° 36'

Consider first the case where

$$\beta L = \left(\frac{2n-1}{4} \right)$$

and where $n=1$. As indicated heretofore, larger values of n merely increase the phase sensitivity, as is desirable, especially if the wave guide is operating fairly near cut-off. The terminations for line L are

$$\frac{1}{Y_1} = Z$$

taken from Table I. Then, for

$$\beta L = \left(\frac{2n-1}{4} \right)$$

the transformed value of Z is Z_t which is

$$Z_t = R_t + i x_t = \frac{R + i(x+1)}{1-x+iR} = \frac{2R+i(1-R^2-x^2)}{1-2x+x^2+R^2} \quad (143)$$

As shown in Figure 13, Z_t is to be parallel resonated with $-ix_6$

5

$$Y_t = \frac{1}{Z_t} = g_t + i b_t \quad (144)$$

and

10

$$Y_6 = \frac{1}{ix_6} = ib_6 \quad (145)$$

When Y_t and Y_6 are connected in parallel the resultant admittance is

15

$$Y \equiv Y_t + Y_6 \quad (146)$$

or

20

$$Y = g_t + i(b_t + b_6) \quad (147)$$

where

25

$$b_t = \frac{x_t}{R_t^2 + x_t^2}$$

25

$$g_t = \frac{R_t}{R_t^2 + x_t^2} \quad (148)$$

30

$$b_6 = \frac{1}{x_6}$$

At resonance $b_t + b_6 = 0$, so that, from Equation 148

35

$$x_6 = \frac{R_t^2 + x_t^2}{x_t} \quad (149)$$

At any other frequency x_t and R_t become x and r , respectively, and the parallel impedance becomes

40

$$Z_1 = \frac{\frac{R_t^2 + x_t^2}{x_t} \left[R_t^2 + x_t^2 + i \left((R_t^2 + x_t^2) \frac{x - (r^2 + x^2)}{x_t} \right) \right]}{r^2 + \left[x - \left(\frac{R_t^2 + x_t^2}{x_t} \right) \right]^2} \quad (150)$$

The impedance Z_1 is the final impedance applied to the oscillator either directly or through a coupling line or circuit. Values of Z_t and Z_1 for various values of Y_2 are shown in Table 2.Table II
Resonator terminations $a_0 Z_k$ for line L_3 in Figure 5c.

$$\beta L = \frac{2n-1}{4}$$

$$\beta L_3 = \pi \times$$

$$Y_2 \text{ (normalized)} = \frac{1}{a_0}$$

$$Y_1 \text{ in Equation (31)}$$

5.0 (1-i)	1.42 - i. 056 = 1.42 / -2° 15'	(.619 + i. 1565) Z_k

Comparing the initial phase angle of the resonator, Y_2 , and the phase angle of the control impedance Z_1 , it is evident that the resonance characteristic of Z_1 is not symmetrical about the resonant frequency, but becomes approximately so in the region $Y_2=0.2$ to 0.1. Also, the phase angle change of the loaded resonator Z_1 in the same region $Y_2=0.2$ to 0.1 is equal to, or greater than, the original change in phase angle of Y_2 .

It is possible to improve the symmetry about resonance by operating with $\beta L_3 \approx 13^\circ 30'$ for which $Y_1=1$, but only at the expense of reduced rate of change of phase angle of Z_1 . Use of an iris to provide a lumped reactance in βL_3 to provide the equivalent of operating βL_3 at length $\beta L_3 = nr + 13^\circ 30'$, is possible.

The entire control network may be considered as a network made up of passive elements, and the insertion loss, defined in usual fashion, may then be computed. For the insertion loss to be significant it is necessary for the controlled oscillator to operate on the same point on its characteristic, and at the same frequency, with and without stabilizer.

The maximum power output for the oscillator, with potential e , working into a matched termination R_0 is

$$P = \left(\frac{eR_0}{R_0 + R_0} \right)^2 \frac{1}{R_0} = \frac{e^2}{4R_0} \quad (151)$$

which may be employed as a reference condition. The power delivered to a matched termination when the stabilizer is inserted may be computed readily. The difference in the power is the insertion loss. The power delivered to a matched termination for various values of Y_2 is shown in Table III. Insertion loss as a function of Y_2 is shown in the graph of Figure 14.

Table III

Resonator terminations $a_0 Z_k$ for line L_3 in Figure 7.

$$Y_2 \text{ (normalized)} = \frac{1}{a_0}$$

Y_2	Power in Matched Termination	Insertion Loss
.02	$20643 e^2$	74.2
.04	$20789 e^2$	68.4
.10	$21122 e^2$	55.0
.20	$2155 e^2$	38.0
1.0	$2231 e^2$	7.6
5.0	$248 e^2$	0.9
Reference power with no stabilizer is $.25 e^2$.		

A good operating region extends from about $a_0=3$ to about $a_0=10$. The resonance characteristic is not quite symmetrical about the resonance frequency, but the average loaded Q for Z_1 for $a_0=10$ is about .72 times the unloaded Q of the resonator out on line L_3 . If the Q of the resonator is 5,000 to 10,000 initially, stabilization to fractions of 1 megacycle per second in 10,000 megacycles per second for reasonable variations in operating parameters is feasible. For $a_0=10$ the insertion loss is 55%. The average loaded Q for the "synthetic resonator" Z_1 , for $a_0=5$, is about one times the unloaded Q of the initial resonator and the resonance characteristic again is not quite symmetrical about the resonance frequency. At $a_0=5$ the insertion loss is 38%.

The performance does not change rapidly for values of a_0 between about three and ten. For a value of $a_0=3$, the insertion loss is about 23%. The final choice of a_0 is a compromise. Operation is somewhat better for $a_0=5$ to $a_0=10$, but not

tremendously better than for $a_0=3$. Therefore, any value of a_0 between about 3 and 10 is satisfactory.

The case where

$$\beta L = \frac{2n-1}{2} \pi$$

should be considered. For the same various values of a_0 , take as terminations for line L values of

10

$$\frac{1}{Y_1}$$

from Table I. For simplicity, consider the case where $n=1$. It is evident that the line transforms

15

$$\frac{1}{Y_1}$$

to Z_t , which is (normalized)

$$Z_t = Y_1 \quad (152)$$

20

As before, corresponding values of Z_1 , the control impedance may be computed from Equation 150. The results are shown in Table IV. Comparison of phase angles for Y_2 at resonance and at frequencies $\frac{1}{2}Q$ above and below resonance, with the corresponding phase angles of Z_1 , indicates that the rate of phase angle change with frequency is much slower for Z_1 than for Y_2 . Also conditions are much worse than those in Table II where L was

30

$$\frac{2n-1}{4} \pi$$

Table IV

Resonator terminations $a_0 Z_k$ for line L_3 in Figure 7.

35

$$L = \frac{2n-1}{2} \pi$$

$$\beta L_3 = n\pi$$

55

Equations 68 which lead to the results of Equations 90 and 91 indicate that a line $\beta L = n\pi$ will not give good results. This prediction may be checked by numerical calculations. For

60

$$\beta L = (2n-1)\pi$$

and the special case where $n=1$

65

$$Z_t = \frac{1}{Y_1}$$

which is the normalized value of Z_t . The results are shown in Table V. As predicted by the general analysis, the rate of phase angle change of Z_1 with frequency departures above and below the resonant frequency by $\frac{1}{2}Q$ is less than the rate of phase angle change of Y_2 , and much poorer than the results shown in Table II. Accordingly, the line βL should be

$$\frac{2n-1}{4} \pi$$

in length. As indicated heretofore, n should be greater than unity to utilize the greater phase sensitivity of a longer line. Also, it is advisable to have the wave guide operate fairly near cut off so that the rate of change of wavelength in the guide is greater than the rate of change of frequency or of free space wavelength.

METHOD IV—COUPLING OF STABILIZER TO OSCILLATOR

Any of the usual types of coupling to the oscillator may be used. In the case where the oscillator is a magnetron a particularly useful type of coupling is shown in Figure 15. A coupling loop, not shown, is placed in and tightly coupled to the magnetron cavity or cavities and connected to a concentric line. The outer conductor 5 of the concentric line is terminated in the lower wall 7 of the wave guide as shown. The inner conductor 9 extends up into the guide a length L_a . As before, the width of the guide is a and the height is b . The coupling loop in the magnetron cavity, length of concentric line and antenna of length L_a will, in general, present an impedance which can be represented by a complex number of the form

$$Z_{int}=R_{int}+ix_{int} \quad (154)$$

By proper choice of distance h of the reactive stub 10, the reactance x_{int} may be tuned out so that Z_{int} becomes

$$Z_{int}=R_{int} \quad (155)$$

The greatest change in operating frequency of the magnetron cavity results when the current in the coupled concentric line 5, 9 goes through its maximum value. This condition should occur if the radiation resistance of the antenna L_a goes through zero. This condition results, in turn, if the guide impedance in the plane A—A goes through zero.

If the antenna radiation resistance does become zero, or approximately zero, the power output of the magnetron will be very adversely affected. Therefore the radiation resistance chosen must be a compromise between a very low value which would give remarkable stabilization, and a somewhat higher value which will still provide acceptable stabilization.

Inspection of Table II, especially in the

recommended region $a_0=3$ to 5, indicates that this second condition may be met. The problem may be considered from either the point of view of the antenna L_a and the effect thereon of the impedance Z_1 coupled to it by the guide, or, from the point of view of the impedance Z_1 and the effect thereon of the antenna coupled to it. In either case, by proper choice of h in Figure 15 the reactance x_{int} must be cancelled out so that only R_{int} remains. Also, in either case the coupling factor k_a of the antenna L_a to the guide will appear as follows:

$$k_a=2\left(\frac{L_a}{b}\right)^2 \sin^2 \frac{\pi d}{a} \quad (156)$$

where a , b , and d are indicated in Figure 15.

If standard X-band wave guide, $L_a=\lambda/4$ at the operating frequency 9210 megacycles per second, and $d/a=1/2$ are employed, then

$$k_a=2(.795)^2 \sin^2 \pi/2=1.265 \quad (157)$$

In the first instance, the antenna of resistance R_{int} has connected to it the external impedance Z_1 , but the coupling factor k_a enters to make the equivalent external impedance $k_a Z_1=1.265 Z_1$.

In the second instance, the impedance Z_1 has connected to it the resistance R_{int} but again the coupling factor k_a enters to make the equivalent resistance

$$30 \quad \frac{R_{int}}{k_a} = \frac{R_{int}}{1.265} = .79 R_{int} \quad (158)$$

The question of possible improvement in Q or of phase-frequency sensitivity by adding $n\pi$ lengths to the wave guides or transforming guide sections frequently arises in designing circuits.

In a waveguide having cross-sectional dimensions a and b , it is assumed that

$$40 \quad a > \frac{\lambda_0}{2}$$

and

$$b < \frac{\lambda_0}{2}$$

45 where λ_0 is the free space wavelength. If the E vector is initially in a plane parallel to the cross-sectional, or xy , plane only one wave of the form

$$50 \quad E_x = A e^{\gamma z} \sin \frac{n\pi}{a} y \quad (159)$$

will be propagated. The initial electric vector intensity is A , and γ is the propagation constant. No other modes will be propagated. If other modes were propagated the same analysis would hold provided the integrations are changed to accommodate the new E and H distributions.

For 3 cm. waves, the standard 1" x 1/2" wave guide fulfills the conditions

$$60 \quad a > \frac{\lambda_0}{2}, b < \frac{\lambda_0}{2}$$

The length of resonator for $Z=\lambda/2$ is $L=\lambda/2=2b$. Also $a=2b$, thus the end area A_1 is

$$65 \quad A_1=a^2 \quad (160)$$

and the area of the sides carrying current is

$$67 \quad A_2=2aL=2a^2 \quad (161)$$

Assuming a uniform substance for the walls, it follows that the respective end and side resistances are

$$70 \quad R_1=R_0 \quad (162)$$

$$R_2=2R_0 \quad (163)$$

75 Considering the ends first, the current distri-

bution in the y direction is sinusoidal, and the average current along y is

$$I_{ay(xy)} = \frac{I_{\max}}{\pi} \int_0^\pi \sin y dy = \frac{2I_{\max}}{\pi} \quad (164)$$

The average current in a unit area of the sides in the Zy plane will be

$$I_{ay(Zy)} = \frac{I_{\max}}{\pi} \int_0^\pi \sin y dy \cdot \frac{I}{\pi} \int_0^\pi \sin Z dZ = \frac{4}{\pi^2} I_{\max} \quad (165)$$

It follows, therefore, that the energy losses in the ends and sides, from Equations 162, 163, 164, and 165 are as follows:

The energy loss in the ends is

$$J_1 = \frac{4}{\pi^2} I_{\max}^2 R_0 \quad (166)$$

and the energy loss in the sides is

$$J_2 = \frac{16}{\pi^4} I_{\max}^2 (2R_0) \quad (167)$$

so that the ratio of the energy loss in the ends to that in the sides is

$$\frac{J_1}{J_2} = \frac{4I_{\max}^2}{\pi^2} \frac{\pi^4}{16I_{\max}^2} \simeq 1 \quad (168)$$

If the Q of a resonator is defined as

$$Q = \frac{\text{Energy stored in resonator}}{\text{Energy loss in resonator}}$$

then the Q of a standard half wave resonator is

$$Q_{(\lambda/2)} = \frac{J_3}{J_4} \quad (169)$$

where J_3 is the energy stored, and J_4 is the energy loss, in the resonator.

For $L = \lambda/2$, J_4 will be $J_1 + J_2$ so that from Equation 169

$$Q_{(\lambda/2)} = \frac{J_3}{2J_1} \quad (170)$$

For a resonator

$$\frac{n\pi}{2}$$

long the Q becomes

$$Q_{(\frac{n\lambda}{2})} = \frac{(n-1)J_3'}{nJ_1'} + \frac{1}{n} \frac{J_3'}{2J_1'} \quad (171)$$

where the primes place the energy on a per $\lambda/2$ section basis.

Then

$$Q_{(\frac{n\lambda}{2})} = \frac{J_3}{2nJ_1} (2n-1) \quad (172)$$

For the limiting case $n \rightarrow \infty$

$$Q_{(\frac{n\lambda}{2})} = \frac{J_3}{J_1} \quad (173)$$

For the shortest resonator $n=1$, and

$$Q_{(\lambda/2)} = \frac{J_3}{2J_1}$$

so that the improvement in going from $n=1$ to $n=\infty$ is

$$\frac{Q_\infty}{Q_{(\lambda/2)}} = 2 \quad (174)$$

The analysis heretofore has assumed a uniform wall material. Since the ends involve a soldering or welding operation, it probably is more accurate to assume the end wall resistance is about equal to the side wall resistance. Thus, the end wall energy loss is J_5 where

$$J_5 = \frac{4I_{\max}^2}{\pi^2} R_0 \quad (175)$$

and the side wall energy loss is

$$J_6 = \frac{16}{\pi^4} I_{\max}^2 R_0 \quad (176)$$

5 The ratio of energy loss in end walls to energy loss in side walls is

$$\frac{J_5}{J_6} = \frac{4I_{\max}^2}{\pi^2} \frac{\pi^4}{16I_{\max}^2} \simeq 2 \quad (177)$$

10 Therefore,

$$Q_{(\lambda/2)} = \frac{2J_7}{3J_5} \quad (178)$$

where J_7 is the energy stored in the length $\lambda/2$. For

$$L = \frac{n\lambda}{2}$$

$$Q_{(\frac{n\lambda}{2})} = \frac{2J_7'}{3nJ_5'} (3n-2) \quad (179)$$

20 where the primes again denote a per $\lambda/2$ section basis.

For the limiting case $n \rightarrow \infty$

$$Q_{(\infty)} = \frac{2J_7}{J_5} \quad (180)$$

so that the improvement in Q in going from $n=1$ to $n=\infty$ is

$$\frac{Q_\infty}{Q_{(\lambda/2)}} = \frac{2J_7}{J_5} \frac{3J_5}{2J_7} = 3 \quad (181)$$

Equations 174 and 181 show that the Q of a resonator does not increase linearly with the number of half wavelengths of length for an assumed reasonable loss distribution.

This analysis holds only when end wall resistance and side wall resistances are assumed to approach 0.

Equations 172 and 179 indicate that the rate 40 of improvement obtained by adding half wave sections to a resonator beyond 3 or 4 becomes negligible. The same equations, however, indicate that if the ratio of end wall losses to side wall losses is high or higher than that assumed, 45 it may be desirable to add half wave sections beyond this 3 or 4 value.

A first practical circuit configuration of the invention, adapted to waveguide construction, is illustrated in Figures 16 and 17.

50 An ultra-high frequency generator comprising a conventional magnetron 11, of which the magnetic structure is omitted for the sake of simplicity, is coupled to a transmission waveguide system 13 which is coupled to a load, not shown.

55 The output coupling line 12 of the magnetron 11 includes a coupling loop, not shown, which is closely coupled to one or more of the magnetron resonant anode cavities. The end of the magnetron output line 12, remote from the magnetron

60 proper, is terminated in a short antenna 15 which extends into the waveguide transmission system 13. Reactance in the magnetron output line 12 is cancelled by means of a reactive stub 17 opening into the waveguide transmission line 13 adjacent the magnetron antenna 15, whereby the magnetron output is made substantially resistive

65 at the plane A-A of the antenna in the waveguide system. The load is matched approximately to the waveguide transmission system 13 by

70 means of a first conventional tuning screw 19 extending through the waveguide wall adjacent the load connection.

The stabilizing network includes a closed waveguide reactive high "Q" stub 21 extending normally from and opening into the transmission

75

Line 13 at a point intermediate the load and a generator. The reactance of the control stub 21 is adjustable by means of a second tuning screw 23. The degree of coupling from the control stub 21 to the transmission line 13 is determined by a coupling aperture device 25 in the tuning stub waveguide adjacent the point where it opens into the transmission waveguide 13. The plane B-B of the control stub 21 is selected to be some multiple of one-half wavelength plus or minus $\frac{1}{8}$ wavelength from the plane A-A of the magnetron antenna. Thus, by means of a third tuning screw 27 extending into the transmission waveguide 13 intermediate the planes B-B and A-A, the effective transformation of the impedance of the control stub 21 provided by the impedance transformer 14, comprising the portion of the waveguide system 13 intermediate the planes A-A and B-B, may be adjusted at the plane A-A which is effectively the resistive termination of the magnetron antenna. The reactive stub 21 and second tuning screw 23 may be considered to be a resonator only as seen from the coupling aperture 25. At the plane A-A of the magnetron antenna, the combination of the stub and tuning screw appear as an impedance.

A fourth tuning screw 29 extending into the transmission waveguide 13 on the opposite side of the plane A-A from the plane B-B of the control stub 21 provides means whereby the transformed impedance of the control stub may be resonated in the plane A-A at the output frequency of the generator 11.

The characteristics of the control stub 21 and the second tuning screw 23 coupled thereto are selected to have relatively high reactance with as high a "Q" value as conventional construction will permit. Thus, by means of the impedance transformation provided by the transformer 14 between the planes B-B and A-A, the resultant reactance at the plane A-A due to the control stub 21 will be substantially lower than the reactance of the control stub itself and will have a substantially higher "Q" value. The transformed reactance at the plane A-A thus may be resonated by means of the fourth tuning screw 29 effectively to provide an extremely high "Q" resonator at the plane A-A which will be effectively connected in shunt with the resonant cavity anode of the magnetron 11 through the coupling line which includes the antenna 15.

The characteristics of waveguide T junctions are well known and are discussed in detail in the literature. Similarly, the reactive effects of tuning stubs coupled into waveguide transmission systems are well known as is the specific structure of such reactive devices. Detailed construction and theoretical consideration of appropriate tuning screws is included in the co-pending application of Vernon D. Landon, Serial No. 508,229, filed October 29, 1943, Patent Number 2,427,107, which is assigned to the same assignee as the instant application.

In operation, the magnetron 11 is adjusted by any conventional frequency adjusting means included therewith to provide the desired output frequency. The first tuning screw 19 is adjusted to provide adjustment of the load coupling impedance to match approximately the load to the transmission waveguide 13, and to permit nearly symmetrical tuning on either side of resonance by the second tuning screw 23. The second tuning screw 23 in the control waveguide stub 21 is adjusted to tune the control impedance to resonance, as viewed from the aperture 25, at

the operating frequency, as may be determined partially by initial calculations. The fourth tuning screw 29 then is adjusted to resonate the control impedance at the plane A-A of the magnetron antenna. Next, the third tuning screw 27 is adjusted to vary the impedance transformation at the plane A-A of the magnetron antenna to obtain the highest practicable "Q" value for the control impedance in view of the resistive load thus placed upon the magnetron as explained in detail heretofore. The fourth tuning screw is again adjusted to resonate the control impedance more accurately to the oscillator output frequency. If necessary, the first tuning screw 19 is again adjusted to match the load to the waveguide transmission system 13.

It is assumed that the reactive stub 17 adjacent the magnetron antenna 15 has been pre-calculated or preset to provide the desired cancellation of reactance in the magnetron output line to the antenna 15. If necessary, an adjustable shorting plug 31 may be included in the reactive stub 17 to provide adjustment of the reactance thereof.

In Figure 18 a preferred circuit configuration includes a cylindrical high "Q" control reactance 21' which includes a tuning piston 33, the longitudinal position of which may be adjusted by means of a micrometer screw 35. The control reactor 21' is coupled to a T junction 37 which extends from the narrow side of the waveguide transmission system 13. A second T junction 39 extending from the opposite narrow side of the waveguide system 13 includes a third tuning screw 27 which is employed to vary the coupling of the control impedance 21' to the impedance transformer 14. The first tuning screw 19 is operable through the transmission waveguide wall intermediate the plane B-B of the control impedance and a load, not shown. The magnetron generator has been omitted for the sake of simplicity.

The operation and adjustment of the system is similar to the device described by reference to Figures 16 and 17. However, the cylindrical construction of the control impedance 21' permits a higher "Q" to be obtained from this element with finer adjustment of the control impedance value.

The higher "Q" control impedance results usually in higher values of resonant resistance and higher reactances at the coupling aperture 25 slightly off resonance. This would result in an unfavorable situation if used in the arrangement of Fig. 16 and Fig. 17 in which waveguide branches 13 and 41 are approximately in series as far as the impedance transformer 14 is concerned, since under these conditions the power delivered to the load would be small.

For this reason the T junction of the type shown in Fig. 18, in which the waveguide branches 13 and 37 (with the additional reactance of the stub 39) are approximately in parallel, is used with a high "Q" control impedance 21', since the high impedances are then in parallel with the useful load. Since the impedance transformation and resonating is otherwise similar to that described in Figures 16 and 17, the effective control impedance "Q" at the plane A-A is substantially improved, thereby providing greater stabilization of the generator frequency, as indicated heretofore.

Thus the invention disclosed and explained theoretically herein comprises several embodiments and modifications of a frequency stabilizer

for wave generators, or of "synthetic resonators" wherein an impedance represented by a complex number is selected, transformed to a new impedance with a higher "Q" and lower absolute value, and then parallel resonated with another reactance having opposite sign. This "synthetic" control resonator is used to stabilize the frequency of the generator. Circuits having rapid rates of change of phase angle with frequency are employed, and critical optimum line lengths are determined to provide a practical circuit configuration. The instant invention appears to differ from prior art devices wherein a high "Q" control is used directly, or wherein the elements of a resonator are combined first and then transformed to new values.

It should be understood that several sections of the circuit configuration described may be cascaded, but circuit adjustment may become very difficult.

I claim as my invention:

1. The method of employing a control impedance for stabilizing the frequency of a signal generator comprising the steps of transforming the value of said impedance to a lower impedance value having a relatively higher Q, resonating said transformed impedance substantially to said generator frequency, and shunting said generator by said resonated transformed impedance.

2. The method of employing a control impedance for stabilizing the frequency of a signal generator comprising the steps of transforming the value of said impedance to a lower impedance value having a relatively higher Q, resonating said transformed impedance substantially to said generator frequency, shunting said generator by said resonated transformed impedance, and cancelling normal coupling reactance between said generator and said resonated transformed impedance.

3. The method of utilizing a control impedance for stabilizing the frequency of a signal generator coupled to a load comprising the steps of cancelling normal coupling reactance from said generator, transforming the value of said impedance to a lower impedance value having a relatively higher Q, resonating said transformed impedance substantially to said generator frequency, and shunting said reactance cancelled generator coupling by said resonated transformed impedance.

4. The method of utilizing a control impedance for stabilizing the frequency of a signal generator coupled to a load comprising the steps of cancelling normal coupling reactance from said generator, transforming the value of said impedance to a lower impedance value having a relatively higher Q, resonating said transformed impedance substantially to said generator frequency, shunting said reactance cancelled generator coupling by said resonated transformed impedance and coupling said load to said generator through said impedance transformation.

5. The method of utilizing a control impedance for stabilizing the frequency of a signal generator coupled to a load comprising the steps of cancelling normal coupling reactance from said generator, transforming the value of said impedance to a lower impedance value having a relatively higher Q, resonating said transformed impedance substantially to said generator frequency, shunting said reactance cancelled generator coupling by said resonated transformed impedance, coupling said load to said generator through said impedance transformation and matching said load to said load coupling.

6. The method of effectively synthesizing a high Q resonant network including an impedance element comprising the steps of transforming the impedance value of said element to a lower impedance value having a relatively higher Q value, and resonating said transformed impedance.

7. A high Q resonant network including a high Q impedance element, means for transforming the impedance value of said element to a lower impedance value having a relatively higher Q value, and reactive means connected to said transforming means for resonating said transformed impedance.

8. Apparatus for stabilizing the frequency of a signal generator, including a high Q control impedance element, means for effectively transforming said impedance to a lower impedance having a relatively higher Q value, reactive means resonating said transformed impedance substantially to said generator frequency, and means for connecting said resonated transformed impedance in shunt with said generator.

9. Apparatus for stabilizing the frequency of a signal generator having a frequency determining resonant element, including a high Q control impedance element, means for effectively transforming said impedance to a lower impedance having a relatively higher Q value, reactive means resonating said transformed impedance substantially to said generator frequency, and means for connecting said resonated transformed impedance in shunt with said generator resonant element.

10. Apparatus for stabilizing the frequency of a signal generator having a frequency determining resonant element, including a load coupled to said generator, a high Q control impedance element, means for effectively transforming said impedance to a lower impedance having a relatively higher Q value, reactive means resonating said transformed impedance substantially to said generator frequency, and means for connecting said resonated transformed impedance in shunt with said generator resonant element and said load.

11. Apparatus for stabilizing the frequency of a signal generator having a frequency determining resonant element, including a load, a transmission line coupling said generator resonant element to said load, a high Q control impedance element coupled to said line, an impedance transformer connected to said control element for providing an effectively lower impedance and a relatively higher Q value, means for providing a resistive termination of said generator at a predetermined point on said line, and reactive means for resonating said transformed control impedance to said generator frequency at said point on said line.

12. Apparatus for stabilizing the frequency of a signal generator having a frequency determining resonant element, including a load, a transmission line coupling said generator resonant element to said load, a high Q control impedance element coupled to said line, an impedance transformer interposed in said line between said control impedance element and said generator for providing an effectively lower impedance and a relatively higher Q value, means for providing a resistive termination of said generator at a predetermined point on said line, and reactive means for resonating said transformed control impedance to said generator frequency at said point on said line.

13. Apparatus as described in claim 12 includ-

ing adjustable means for matching the impedance of said load to said transmission line.

14. Apparatus for stabilizing the frequency of a signal generator having a frequency determining resonant element, including a load, a transmission waveguide coupling said generator resonant element to said load, a high Q adjustable control impedance element coupled to said waveguide, a section of said waveguide providing an impedance transformer interposed between said control impedance element and said generator for providing an effectively lower impedance and a relatively higher Q value, means for providing a resistive termination of said generator at a predetermined point on said waveguide, and reactive means for resonating said transformed control impedance to said generator frequency at said point on said waveguide.

15. Apparatus for stabilizing the frequency of a signal generator having a frequency determining cavity resonator, including a load, a transmission waveguide coupling said general cavity resonator to said load, a high Q control reactive cavity element coupled to said wave guide, a section of said wave guide providing an impedance transformer interposed between said control reactive cavity element and said generator for providing an effectively lower impedance and a relatively higher Q value, means for providing a resistive termination of said generator at a predetermined point on said wave guide, and reactive means for resonating said transformed control impedance to said generator frequency at said point on said wave guide.

16. Apparatus for stabilizing the frequency of a signal generator having a frequency determining cavity resonator, including a load, a transmission wave guide coupling said generator cavity resonator to said load, a second waveguide forming a T junction with said transmission waveguide and comprising a high Q control reactive cavity element coupled to said wave guide, a section of said wave guide providing an impedance transformer interposed between said control reactive cavity element and said generator

45

for providing an effectively lower impedance and a relatively higher Q value, means for providing a resistive termination of said generator at a predetermined point on said wave guide, and reactive means for resonating said transformed control impedance to said generator frequency at said point on said wave guide.

17. Apparatus for stabilizing the frequency of a signal generator having a frequency determining cavity resonator, including a load, a transmission wave guide coupling said generator cavity resonator to said load, a T junction in said wave guide, a cylindrical high Q control reactive cavity element of adjustable volume coupled through said junction to said wave guide, a section of said wave guide providing an impedance transformer interposed between said control reactive cavity element and said generator for providing an effectively lower impedance and a relatively higher Q value, means for providing a resistive termination of said generator at a predetermined point on said wave guide, and reactive means for resonating said transformed control impedance to said generator frequency at said point on said wave guide.
